ATTORNEY.

UNITED STATES PATENT OFFICE.

DE WANE B. SMITH, OF DEERFIELD, NEW YORK.

DESIGN FOR A SPRAYER-BODY.

SPECIFICATION forming part of Design No. 29,623, dated November 8, 1898.

Application filed October 17, 1898. Serial No. 693,841. Term of patent 8½ years.

To all whom it may concern:

Be it known that I, DE WANE B. SMITH, a citizen of the United States, and a resident of the town of Deerfield, in the county of Oneida and State of New York, have invented and produced a new and original Design for the Bodies of Sprayers, of which the following is a specification, reference being had to the accompanying drawings, forming a part thereof.

Figure 1 shows a perspective view of a sprayer-body of my present design. Fig. 2 shows a side elevation of the same.

As shown in the drawings, the leading or material features of my design consist of the long cylindrical portion 1 and the square rectangular portion 2, arranged at one end of

the portion 1 with the ends converging and meeting, as shown, and the depending end of the part 2 held to the part 1 by the connecting-piece 3.

Having described my invention, what I claim as new, and desire to secure by Letters Patent, is—

The design for a body of a sprayer, as herein shown and described.

In witness whereof I have hereunto set my hand, in the presence of two witnesses, this 7th day of October, 1898.

DE WANE B. SMITH.

Witnesses:

E. W. JONES,
SARAH A. BROWN.
